United States Patent Office.

JAMES C. ADAMS, OF PHILADELPHIA, PENNSYLVANIA.

Letters Patent No. 65,855, dated June 18, 1867.

IMPROVED METALLIC-PAINT KEG.

The Schedule referred to in these Letters Patent and making part of the same.

TO ALL WHOM IT MAY CONCERN:

Be it known that I, JAMES C. ADAMS, of the city of Philadelphia, in the State of Pennsylvania, have invented a new and useful improved Metallic-Paint Keg; and I do hereby declare that the following is a full and exact description thereof, reference being had to the annexed drawings, forming part hereof.

The drawings represent a vertical section of my improved keg, which is designed to be used by manufacturers as vessels to pack paint in, and afterwards by painters as vessels to mix in and paint from.

I turn over the edge of the keg flat, making two turns, as shown at *a* in the drawings. When so formed the top presents a rounded surface for the painter to clean his brush upon without cutting it. The increased thickness of the top adds to the strength of the keg, and the top being flat, it allows close contact between the cover and the body of the keg.

Having thus described my invention, I claim, and desire to secure by Letters Patent—

A metallic-paint keg having its top formed by turning over the edge thereof flat twice, substantially as shown and described.

JAS. C. ADAMS.
